(57) CLAIM

What is claimed is the ornamental design for a baseball figurine, as shown.

DESCRIPTION

FIG. 1 is a frontal view of a baseball figurine illustrating the new design;

FIG. 2 is a left side view thereof;

FIG. 3 is a right side view thereof;

FIG. 4 is a rear view thereof;

FIG. 5 is a top view thereof; and,

FIG. 6 is a bottom view thereof.

The broken line showing of the baseball figurine is included for the purpose of illustrating environmental structure and forms no part of the claimed design.
